INVENTOR.
Richard Garvey.

Alan Franklin

ATTORNEY.

UNITED STATES PATENT OFFICE.

RICHARD GARVEY, OF LOS ANGELES, CALIFORNIA.

ROTARY SWING OR CAPTIVE AEROPLANE.

Application filed November 6, 1926. Serial No. 146,659.

This invention relates to amusement devices and particularly to a rotary swing of the captive aeroplane type.

The general object of the invention is to provide a rotary amusement device including a plurality of suspended swings which, not only swing outward from their points of suspension, but also travel outwardly and upwardly together with their points of suspension under the influence of centrifugal force, thus giving the occupants of the swing a novel and exciting thrill.

A more particular object is to provide an attachment which may be attached to the ends of the radial arms of an amusement device of the rotary swing type, by means of which attachment additional swings may be suspended between the conventional swings of the device, so that such additional swings may, not only swing outwardly from their points of suspension, but also may swing outwardly and upwardly together with their points of suspension under the influence of centrifugal force.

Other objects and advantages will appear hereinafter as the description progresses.

The invention is illustrated in the annexed drawing which forms a part of this specification and in which,

Fig. 1 is a perspective of a rotary swing of the captive aeroplane type embodying my invention.

Fig. 2 is a side elevation of my attachment shown attached to the outer end of a radial arm of a rotary swing.

Fig. 3 is a transverse vertical section taken on line 3—3 of Fig. 2.

Corresponding reference characters designate the same parts in all the figures.

In Fig. 1 I have illustrated a rotary swing of the conventional type, comprising a tower structure 1, a vertical shaft 2, extending upwardly through the top of said tower and journaled in a bearing 3 in the upper end of the tower, a spider 4 comprising a hub 5 and a plurality of arms 6 extending radially from said hub which hub is secured on the shaft 2 and rests upon the bearing 3, and a plurality of swings 7, in the form of aeroplanes, suspended from the ends of the arms 6 by means of cables 8, each of said swings being suspended by a pair of said cables between a pair of adjacent arms.

My invention includes a track bar 10, formed with a vertical securing flange 11 at its inner end and with arcuate stops 12 and

13 at its inner and outer ends respectively, a roller 14 mounted to travel on said track, a shackle 15 vertically suspended at its upper end from a shaft 16 on which said roller is journaled, an eye 17 swivelly connected at 18, to the lower end of said shackle below said track bar, a pair of cables 19 and 20 suspended at their upper ends from the eye 17, and a swing 21 in the form of an aeroplane suspended from the lower ends of said cables.

The securing flange 11 is secured by bolts 22 to the head 23 on the outer end of a spider arm 6, and the track bar 10 extends outwardly and upwardly at an angle from said securing flange. The stops 12 and 13 extend upwardly from the track 10. The track 10 is T-shape in cross section, its vertical flange 24 extending upwardly from its transverse flange 25 which serves to reinforce the track.

The roller 14 rests upon the upper edge of the vertical flange 24 of the track 10 and said roller is formed with flanges 26 and 27 at its sides respectively, which flanges depend below the upper edge of the track flange 24 over the sides respectively of said flange to prevent the roller running off the track. The shackle 15 extends downwardly past opposite sides of the track 10 and under the track as shown in Fig. 3. A swing 21 suspended from a roller 14 on a track 10 is suspended between two swings 7. Tracks 10 are respectively secured to the ends of the arms 6 and from said tracks swings 21 are respectively suspended between adjacent swings 7.

When the swing is rotated all the swings 7 and 21 swing outwardly under centrifugal force from their points of suspension, the swings 21 swinging from the roller shafts 16 as pivots. As the speed of rotation of the swing increases the rollers 14 travel outwardly on the tracks 10 until arrested by the stop 13. The swings 21, thus not only swing outwardly from their points of suspension, but travel bodily outward together with their points of suspension under the influence of a supercentrifugal force, giving the occupants of the swings a novel and exciting thrill.

While my invention is shown attached to a conventional swing it is not restricted to such use. The invention may be constructed in a device by itself and without the swings 7.

It is obvious that variation and modifica-

tions of the invention may be made without departing from the spirit of the invention.

Having thus described my invention, I claim:

1. In combination with a rotary swing, including a rotary arm with a head on its outer end, a track bar formed with a flange on its inner end and with stops, one at its outer end and another near its inner end, 10 said flange being bolted to said head with the track bar extending outwardly from said arm, a roller mounted to travel on said track bar between said stops, a swing, and means for suspending said swing from said roller.

2. In combination with a rotary swing including a rotary arm, a track bar formed with a stop at its outer end and a stop at its inner end, means for securing said track bar at its inner end to the outer end of said rotary arm, a roller mounted to travel on said track bar between said stops, a shackle pivotally suspended from the axis of said roller, a ring swivelly connected to the lower end of said shackle, cables extending through said ring, and a swing connected to the lower 25 end of said cables.

RICHARD GARVEY.
